UNITED STATES PATENT OFFICE.

ANNIE STRAUS, OF DANVILLE, ILLINOIS.

HAT-FASTENER.

957,810.

Specification of Letters Patent. Patented May 10, 1910.

Application filed November 28, 1908. Serial No. 464,880.

To all whom it may concern:

Be it known that I, ANNIE STRAUS, a citizen of the United States, residing at Danville, in the county of Vermilion and State 5 of Illinois, have invented new and useful Improvements in Hat-Fasteners, of which the following is a specification.

This invention relates to hat fasteners, the object of the invention being to provide a 10 simple, practical and reliable device for ladies, so in securing hats upon the head, the fastening means may be connected with and carried by the hat thus avoiding the necessity of puncturing the crown of the 15 hat with numerous holes.

A further object of the invention is to so connect the fastening device with the hat as to provide elasticity which will form a yielding connection between the fastening 20 device and the hat to more effectively prevent the hat from becoming detached from the hair.

With the above and other objects in view, the invention consists in the novel construction, combination and arrangement of parts as herein fully described, illustrated 25 and claimed.

In the accompanying drawings:—Figure 1 is a cross section through a hat showing 30 the improved fastening means applied thereto and the relation thereof to the hair. Fig. 2 is a detail perspective view of one member of the hat fastening device showing also one of the elastic connectors.

Referring to the drawings, 1 designates a 35 hat of any suitable description to which the fastening device is permanently connected. The fastening device comprises a pair of similar hat pin members each of which is 40 formed as shown in Fig. 3 of a continuous piece of wire bent to comprise substantially parallel portions 3 which are connected together at one end as shown at 4 by a rounded extremity 45 of the member, while at the opposite end the member is provided with an enlarged eye 5 adapting the same to be loosely attached to an elastic connector 6. In other words the pin consists of a loop-shaped shank and an 50 eye-shaped head, the opening of which communicates with the opening of the shank.

The connector 6 consists of a suitable length of elastic webbing which is folded upon itself to form a loop as shown in Fig. 55 2 the loop passing through the enlarged eye 5 of the hat pin member while the extremi-

ties of the connector are stitched or otherwise fastened together and also secured to the inner side of the crown of the hat in the manner indicated in Fig. 1.

60

It will be understood by reference to Fig. 1 that two of such hat pin members are employed and made of suitable length to overlap each other at their inner ends after they have been inserted in the hair.

65

Before placing the hat on the head the pins are slipped outwardly through the flexible attaching loop until the headed ends 5 are under the brim of the hat where the pins can be conveniently gripped after the hat is placed on 70 the head and thrust into the hair. In this longitudinal movement of the pin one of the side members 3 will slide freely in the attaching loop 6 and as the loop 6 is flexible the pin can be inserted through the hair 75 transversely or toward the front or rear as will be found most desirable according to the manner in which the hair is dressed, and after the pin is fully inserted the loop 6 will extend transversely to the eye 5 and thus 80 prevent the pin from accidentally working loose.

85

When the hat pin members are completely inserted as shown in Fig. 1, the extremities of such members are embedded in the hair and obtain a sufficiently firm hold thereon to prevent the hat from being blown or otherwise accidentally moved from the head.

The fastening device as a whole is carried by the hat so as to be accessible at all times.

90

I claim:—

The combination of a hat including a crown, with a hat fastener normally disposed in the crown, and a flexible attaching device consisting of a doubled elastic tape 95 having its upper end fastened to the crown and its lower looped end free from the crown and terminating adjacent the bottom edge thereof, said pin consisting of a continuous piece in the form of a looped 100 shank and an eye-shaped head which has its opening communicating with the opening of the shank to permit the pin to move longitudinally into and out of the crown by freely sliding through the attaching loop.

105

In testimony whereof I affix my signature in presence of two witnesses.

ANNIE STRAUS.
